UNITED STATES PATENT OFFICE

171,514

PLATE OR SIMILAR ARTICLE

Toni Olga Muench, East Liverpool, Ohio, assignor to Fisher, Bruce & Company, Philadelphia, Pa., a corporation of Pennsylvania

Application January 23, 1953, Serial No. 23,272

Term of patent 7 years

(Cl. D44—15)

To all whom it may concern:

Be it known that I, Toni Olga Muench, a citizen of the United States, residing in East Liverpool, Columbiana County, and State of Ohio, has invented a new, original, and ornamental Design for Plate or Similar Article, of which the following is a specification, reference being had to the accompanying drawing, forming a part hereof.

Figure 1 is a top plan view of a plate or similar article, showing my new design, one quarter of the border decoration being shown and repeated continuously around the peripheral portion of the plate or similar article.

Figure 2 is a side elevational view of said plate or similar article.

I claim:

The ornamental design for a plate or similar article, as shown and described.

TONI OLGA MUEENCH.
